CLAIM

The ornamental design for a milling machine, as shown and described.

DESCRIPTION

1. Milling machine

1.1 : Front

1.2 : Perspective

1.3 : Perspective

1.4 : Right

1.5 : Left

1.6 : Back

(Continued)

The ghosted areas within the broken lines depict portions of the milling machine that form no part of the claimed design.

1 Claim, 6 Drawing Sheets
